UNITED STATES PATENT OFFICE.

LUKE H. HANCOCK, OF FARGO, NORTH DAKOTA.

SHOE-LACE FASTENER.

SPECIFICATION forming part of Letters Patent No. 701,199, dated May 27, 1902.

Application filed November 30, 1901. Serial No. 84,185. (No model.)

To all whom it may concern:

Be it known that I, LUKE H. HANCOCK, of Fargo, in the county of Cass and State of North Dakota, have invented a new and useful Improvement in Shoe-Lace Fasteners, of which the following is a specification.

My invention relates to an improvement in lace or string fasteners for shoes and other articles, and has for its object to provide a simple and efficient device for securely holding or clamping the loose ends of a lacing or string to the upper part of a shoe or other article, thus obviating the necessity and inconvenience of tying the lacing or strings, and also preventing loosening of the lacing or string, which is a common source of annoyance in articles fastened by lacings or strings.

To this end my invention consists of the peculiar construction, arrangement, and combination of parts, as will be hereinafter fully set forth and claimed, and shown in the drawings hereunto annexed and forming part of this specification, in which—

Figure 1 is a perspective view of the device attached to upper portion of a shoe-upper. Fig. 2 is a central vertical section of Fig. 1. Fig. 3 is a view of the coiled spring and plate-spring removed from the tube or cylinder. Fig. 4 is a central vertical section of a modification. Fig. 5 is a sectional view of a modification.

To the upper portion of a lace shoe or other article at any suitable location where a lacing or string is used a small plate 1 is secured by any suitable means, said plate being preferably about three-fourths of an inch square. To this plate is secured in any suitable manner a small tube or cylinder 2 about one-half inch in length, having both ends open, as shown. Near the upper portion of this tube or cylinder in its front face is cut a transverse slot or opening 3.

To the plate 1 at a point slightly below the lower open end of the tube or cylinder 2 is secured the lower end of plate-spring 4, said spring being bent away from the plate 1 at a point slightly above its point of attachment to said plate 1. The plate-spring then extends upwardly in a diagonal direction through the tube or cylinder and the upper portion 5 thereof, which may be slightly broader than the main portion, is bent forwardly, down-

wardly, and then slightly rearwardly, and terminates in a plurality of the teeth or prongs 5'. In the drawings three teeth are shown, 55 but any suitable number may be used.

A spring is secured at one end to the inside of the tube or cylinder 2 at a point substantially opposite the slot or opening 3 in the opposite face and consists of the contractile 60 spirals 6 and the straight portions 6' and 6''. The last coil of the spirals 6 rests flatly against the rear face of the plate-spring 4, and the extension 6' is then carried to one side a sufficient distance to project through the slot or 65 opening 3, when it is given a return bend and forms the arm 6'' in close relation to the part 6' and grips the plate-spring 4 between it and the extension 6' and the spirals 6. The purpose of the coil-spring 6 and the gripping extensions 6' and 6'' is to pull the upper bent-over portion 5 of the plate-spring, with its teeth 5', toward and against the front face of the tube or cylinder 2 adjacent to its upper edge. 70

The tendency of plate-spring 4 is to spring outwardly and carry the teeth or prongs away from the front face of the tube or cylinder; but, as we have seen, this tendency is opposed and overcome by the contractile coil-spring 80 6 and the extensions 6' and 6'' and the teeth, as stated, drawn against the front face of the tube or cylinder adjacent to the upper edge of the same. 75

The portions 6' and 6'' of the spring lie 85 closely together, and, as stated, hold the plate-spring 5 tightly between them, and the extension 6'' rests in the slot or opening 3 and extends slightly beyond the side walls of the same, forming a finger-piece for the operation 90 of the device.

While the plate 1, which is shown, forms a firm base for the attachment of the tube or cylinder 2, yet it is not absolutely essential, as it may be dispensed with and the tube or 95 cylinder attached directly to the shoe-upper or other article and the lower end of plate-spring could then be secured to the shoe-upper or other article, as shown in Fig. 5; but it would preferably, in a construction where 100 the plate 1 is absent, be secured to the inner face of the tube or cylinder at or near its lower edge.

The fastener may be applied to shoes, gloves,

corsets, leggings, or any other articles where lacings or strings are used.

While I have shown and described 2 as a tube or cylinder, it is obvious that a tubular body of any suitable shape—such as square, semicylindrical, elliptical, &c.—might be used.

The operation of the device is as follows: When the shoe or other article has been laced 10 to near the top, the thumb of one hand is placed on the side of the tube or cylinder 2, contiguous to the bend of the spring-wire, and the forefinger of the same hand is placed on the end of portion 6² and pressed downwardly 15 and outwardly, thus pulling the plate-spring forwardly, and consequently carrying the teeth 5' away from the face of the tube or cylinder 2. The end of the lace or string is then passed upwardly into the lower end of the 20 tube or cylinder, through the same, and over the upper edge and under the teeth 5'. The end of extension 6² is then released, when coiled portion 6 pulls the plate-spring 4 rearwardly and draws the teeth 5' against the lace 25 or string, gripping the same and effectually preventing said lace or string from being accidentally drawn back again. At the same time 6² is pulled back into the slot or opening 3. To release the lace or string, the end 30 6² is pressed downwardly and forwardly, as before, throwing the teeth 5' away from the lacing or string, when it can readily be withdrawn from the tube or cylinder.

The extensions 6' and 6² may be omitted 35 and simply a coiled contractile spring 6³ used, fastened at one end to the inside of the tube or cylinder and at the other to the plate-spring 4, as shown in Fig. 4.

Where a single lace or string is used, one 40 of the fasteners only is necessary; but where a double lace or string is used a fastener may be attached to each side of the opening to be laced or closed.

Having thus described my invention, what 45 I claim as new, and desire to secure by Letters Patent, is—

1. A fastening for lacing-strings comprising a tubular body having open ends and adapted to be secured to a shoe or other article 50 50, a plate-spring secured at its lower end and extending upwardly through the tubular body and over the upper end of the same, teeth or prongs at the upper end of the plate-spring adjacent to the upper edge of the tubular body, and a spring adapted to move the teeth or prongs of the plate-spring toward the outer face of the tubular body.

2. A fastening for laces or strings consisting of an open-ended tubular body, having a 60 transverse slot or opening in its front face and adapted to be secured to a shoe-upper or

other article, a plate-spring secured at its lower end extending upwardly through said tubular body and having a bent-over upper end, teeth or prongs at the end of said bent-over portion, a contractile coiled spring secured at one end to the inner face of the tubular body, said coiled spring provided with an extension clasping the plate-spring and extending transversely across the front face of 70 the tubular body within the slot in the same.

3. A fastening for laces or strings consisting of a base-plate adapted to be secured to a shoe-upper or other article, an open-ended tubular body secured to said base-plate and 75 having a transverse slot in its front face, a plate-spring secured at its lower end to the base-plate and extending upwardly through the tubular body and bent at its upper end, teeth or prongs at the end of said bent portion adjacent to the upper end of said tubular body, a wire spring secured at one end to the inner face of the tubular body having contractile coils extending across the tube, a straight portion bent transversely from the 85 coiled portion, through the slot in the tubular body, a bend and a second straight transverse portion extending in an opposite direction from the first straight portion which with the said first straight portion forms a clasp 90 for the plate-spring and forms a finger-piece for operating the device, substantially as shown and described.

4. A fastener for laces or strings consisting of an open-ended tubular body adapted to 95 be secured to a shoe-upper or other article, a transverse slot in the front face of the tubular body, a plate-spring secured at its lower end, said spring extending upwardly through the tubular body and having a turned-over 100 upper portion provided with teeth or prongs at its end, a wire spring secured at one end to the inner face of the tubular body, contractile coils formed therein, said wire spring having straight transverse oppositely-extending 105 arms adapted to grip the plate-spring between them, and lying in said transverse slot, substantially as shown and described.

5. A fastener for laces and strings consisting of an open-ended tubular body adapted to 110 be secured to a shoe-upper or other article, a plate-spring secured at the lower end, and having the upper end bent over and provided with teeth or prongs adapted to bear against the front face of the tubular body adjacent 115 to its upper edge and means for moving said teeth against the upper portion of the tubular body adjacent to the edge thereof.
